UNITED STATES PATENT OFFICE.

EDWARD AMOS HARRIS, OF WARREN, ARKANSAS, ASSIGNOR OF THREE-EIGHTHS TO
RUPERT GRASBY, OF WARREN, ARKANSAS.

OFFSETTING DEVICE FOR SAWMILL-CARRIAGES.

1,197,367.

Specification of Letters Patent.

Patented Sept. 5, 1916.

Application filed January 29, 1916. Serial No. 75,033.

To all whom it may concern:

Be it known that I, EDWARD AMOS HARRIS, a citizen of the United States, residing at Warren, in the county of Bradley and State of Arkansas, have invented certain new and useful Improvements in Off-setting Devices for Sawmill-Carriages, of which the following is a specification.

My invention relates to an improved mechanism for off-setting the log carriage from the saw when the carriage returns from the cutting operations, and the invention consists in the constructions, arrangements, and combinations of parts herein described and claimed.

The principal object of my invention lies in the provision of an automatically controlled steam operated mechanism for off-setting the log carriage from the cutting saw in a saw-mill when the carriage returns after having carried the log against the saw to cut off a board.

Among other objects and advantages present which will be pointed out in the following specification, my invention includes a pawl and ratchet device which is so arranged as to operate when the time of reversal of travel of the carriage occurs and perform the off-setting function.

In the drawings which form a part of this application:—Figure 1 is a plan view of the log carriage showing it in the position for conveying a log against the cutting saw, a part of the log being indicated in dotted lines. Fig. 2 is a cross section on line 2—2 of Fig. 1 showing the position of the pawl and cam ratchet when the carriage travels forwardly as in Fig. 1. Fig. 3 is a detail section similar to Fig. 2 showing the action of the cam-ratchet on the pawl when the carriage is at the point of reversing. Fig. 4 is a detail section showing the position of the parts after the carriage has reversed. Fig. 5 is a plan view showing the log carriage returning from a cut, the log and carriage being shown off-set from the saw. Fig. 6 is a cross section on line 6—6 of Fig. 1. Fig. 7 is a cross section on line 7—7 of Fig. 1. Fig. 8 is a transverse section on line 8—8 of Fig. 7. Figs. 9, 10, and 11 are cross sections on lines 9—9, 10—10 and

11—11 respectively, of Fig. 7 showing the steam valve and steam port. Fig. 12 is a perspective view of the steam valve.

In the drawings, 1 represents a track rail which has an inverted V-shape bearing surface as shown in Fig. 6 and spaced from the track 1 is another rail 2 which has a flat bearing surface. Wheels 3, having suitable V grooves are mounted on the track 1 while wheels 4 with flat bearing faces are mounted on the track 2. The wheels 3 and 4 support the log carriage 5 and in order to do this are mounted on axes 6 which are disposed at the opposite ends of the carriage 5 and on an axle 7 which is disposed centrally of the carriage as shown in Fig. 1. The axes 6 and 7 are located in suitable bearings 8 which are shown in Figs. 6 and 7, the bearings being mounted beneath the longitudinal side beams of the carriage 5.

End timbers 9, join the ends of the side beams of the carriage 5 and form a rectangular frame of the carriage on which the log α is placed and held in any suitable manner. The cutting saw 10 is preferably a band saw and is disposed near the edge of the carriage 5. The carriage 5 is moved forward along the tracks 1 and 2 so that the log α may be engaged by the saw to cut off a plank γ as shown in Fig. 6. During the operation of cutting the plank, the carriage 5 is located adjacent to the wheels 4 as shown in Figs. 1 and 6 and is forced to remain in this position relative to the axes 6 and 7 by means of the mechanism about to be described. After the plank γ is completely cut off the carriage 5 must return so that the log may again be presented to the saw 10 and another plank cut off. In order to prevent the log from engaging the saw 10 when the carriage makes its return trip, the carriage 5 is offset a distance of approximately five-eighths of an inch. For this purpose the axes 6 and 7 and the wheels 3 and 4 are in a fixed transverse relationship with the saw 10 but the carriage 5 is movable on the axes 6 and 7 with transverse relationship to the saw in order to accomplish the off-setting of the log from the saw. The V-shaped track 1 therefore is the governing line which holds the ground

wheels 3 and their depending parts, in the correct lateral relationship with the saw 10.

The carriage 5 is held adjacent to the wheels 4 so that it may be in the proper position to perform the cutting of the plank y by the pressure of steam against one head of a cylinder 11, one cylinder being located at each of the opposite ends of the carriage 5 where it is secured to the timbers 9.

10 The construction of the cylinders 11 and their co-acting parts is identical and therefore the description of one will suffice for both. The axle 6 passes through the cylinder 11, a sleeve 12, being disposed around 15 the axle as shown in Fig. 7 in which the axle has rotary movement. The sleeve 12 is held from endwise movement with respect to the axle 6 by a pair of clamps 13 which are moved up against the ends of the sleeve 12 20 and bolted into position. Located on a centrally disposed threaded portion of the sleeve 12 is a piston head 14, the piston head 14 and the sleeve 12 being immovable with 25 relationship to the wheels 3 and 4 by the means described above. The cylinder 11 is however, movable with respect to the sleeve 12 and axle 6 and this movement of the cylinder 11 governs the position of the carriage 5 with respect to its relationship with the 30 saw 10. As before stated, Figs. 1 and 6 show the carriage 5 moved near to the saw in order to effect the cutting of a plank from the log. In order to move and keep the carriage 5 into this position until the time 35 for the reversal of the travel of the carriage, steam is admitted into the cylinder 11 as indicated in Fig. 7. The pressure of the steam against the walls of its confinement forces the cylinder 11 to move over in the direction 40 of the arrow in Fig. 7 and since the carriage 5 is secured to the cylinder 11 (there being one cylinder at each end of the carriage) the carriage 5 is thus moved over into the position mentioned. The carriage 5 is held 45 in this position by the pressure of the steam which is constant during the entire travel of the carriage in this direction, the pressure of the steam being about 80 pounds. The even cutting of the plank y is thus assured.

50 Steam is admitted to the cylinder 11 on the side indicated in Fig. 7, by a valve 15 which is located in the bore 26 of the valve chest 16. The valve 15 has a central bore 17 which does not extend the full length of the 55 valve but stops slightly short of the far end and forms the support for the turning stem 18 which passes through a suitable stuffing box arranged in the head of the valve chest. The end of the stem 18 is square and receives 60 the arm 19 by which the valve 15 is turned. The valve 15 is held in position within the bore of the chest 16, by a coupling 20 which has a nipple-like end which receives one end of a steam hose 21. The steam hose connects 65 to a suitable source of steam supply (not

shown) and is made flexible so that it may follow the movements of the carriage 5 as it travels toward and from the saw 10.

The valve 15 is provided with steam ports 22 and 23 each of which is adapted to register with a co-acting steam passage 24 and 25 in the valve chest when the valve 15 is turned in a manner to be described. One end of each of the passages 24 and 25 must of course communicate with the bore 26 of the valve chest, while the other ends of the passages communicate with the bore of the cylinder 11 at opposite sides of the piston shown in Fig. 7, in which figure steam passes through the port 22 into the passage 24 with which it is now in registration, into the left end of the cylinder 11 and forces the cylinder 11 and the attached carriage 5 over as hereinbefore explained. Steam is exhausted from the other end of the cylinder 11 when the cylinder is moved over as in Fig. 7, through the passage 25. When the valve 15 was turned to admit steam into the left end of the cylinder 11, a branch 27 of the semi-annular exhaust passage 28 came into registration with the steam passage 25 and completed a pathway for the exhaust steam to the exhaust pipe 30 (see Fig. 10). Another branch 29 extends from the exhaust passage 28 but in an opposite direction from the branch 27. The openings in each of the heads of the cylinder 11 through which the sleeve 12 passes, are made steam-tight by a suitable stuffing box 31 as shown in Fig. 7.

100 It has been shown that the cylinder 11 and the carriage 5 has been moved by the turning of the valve 15 so as to bring the port 22 into registration with the passage 24 and permit the entrance of steam into the left side of the cylinder. The valve 15 was turned to this position at the moment when the carriage 5 was reversed in its travel along the tracks 1 and 2, to again move the log x toward the saw 10. The 105 turning of the valve 15 is effected by shifting its attached arm 19 which is connected to a bar 32 of a pawl frame 33 by a connecting rod 34 (see Figs. 2 and 8).

The pawl frame 33 consists of a pair of 110 arms 35 and 36, each of these being pivotally mounted on a rod 37 and 38 each of which has a suitable secure fastening in the beams of the carriage 5. The arms 35 and 36 are located at even distances on each side of the 115 centrally disposed axle 7 and each of the respective arms 35 and 36 has a pawl 39 and 40 which extends toward the axle 7 and co-operates with co-acting cam-ratchets 41 and 42 respectively. Each of the cam-ratchets is divided centrally so that it may readily be clamped to the axle 7 or removed therefrom, a suitable clamping collar 43 being formed on each cam-ratchet for this 120 purpose.

The peripheries of the cam-ratchets 41 and 42 act as cams on the shanks of their co-acting pawls 39 and 40 at a certain time. The periphery of the cam 41 is provided 5 with a plurality of depressions of which 44 is the more abrupt side and forms a shoulder which is adapted to engage a shoulder 45 of a head formed on the end of the pawl 39 and on an angle similar to that of the shoulder 44. The pawl 39 is pressed into engagement with the cam 41 by a spring 46 which is secured at one end to the arm 35 as shown. The face of the cam 42 is provided with a plurality of depressions of which, 47 is the 10 more abrupt side and forms a shoulder which is adapted to engage a shoulder 48 of a head on the other pawl 40 the shoulders 47 having an angle of inclination similar to that of the shoulder 48 and the shoulders 44 of 15 the cam 41, it being noted, however, that the shoulders 47 of the cam 42 are disposed in opposite inclination to that of the shoulders 44 of the cam 41. This arrangement is for the obvious reason that the pawls 39 and 40 20 are arranged at opposite sides of the cams 41 and 42 and the shoulders as above described are so arranged that they may be engaged by the pawl shoulders 45 and 48 respectively at the periods of reversal of the 25 carriage 5 from its forward travel and vice versa. The pawl 40 is pressed into engagement with its co-acting cam 42, by a spring 49. The valve mechanism for the cylinder 11 at the left of Fig. 1, is operated by a 30 connecting rod 50 in a similar manner to that in which the valve mechanism of the cylinder 11 at the right of Fig. 1 and in Fig. 7, is operated.

The method of operation of the device is 40 as follows:—The carriage 5 is moving forward toward the saw 10 as shown in Fig. 1, and in order to present the log α to the saw in the proper manner to cut off a plank, the carriage has been moved over from the governing line rail 1 adjacent to the saw 10 in the manner previously described. At this time the axle 7 and its carried cams 41 and 42 are rotating in the direction of the arrow in Fig. 2. As soon as the carriage 5 reaches 45 the end of its movement toward the saw and the plank is completely cut from the log α , the direction of the movement of the carriage must be reversed so as to return the log for another cutting operation. This reversal 50 of the carriage is effected by any suitable mechanism, not shown. It is at the moment of this reversal of the carriage 5 that it is necessary to offset the log and consequently the carriage 5 so that when the carriage 55 returns, the log α will not rub against saw 10.

In Fig. 3 the axle 7 is shown as just beginning to rotate in a direction opposite to that in Fig. 2, this change in the rotation being caused by the reversal of the travel of 60 the carriage 5. In the position shown in

Fig. 3, the shoulder 47 of one of the depressions in the periphery of the cam 42 has just engaged the shoulder 48 of the pawl 40 which is pivoted on the arm 36 of the pawl frame 33. The shoulder 47 will now cause 70 the pawl 40 and the arm 36 to move over in the direction of the arrow in Fig. 3 and commence to urge the connecting rod 34 toward the right. Moving the rod 34 as stated, will shift the arm 19 in the direction of the arrow in Fig. 8 and thus bring the port 23 of the valve 15 into registration with the steam passage 25. Steam will now enter the right side of the cylinder 11 in Fig. 7 and force the cylinder in a direction opposite to the 75 arrow and since the cylinder 11 is secured to the carriage 5, it is obvious that the carriage will become off-set from the saw 10 and allow the log α to move backwardly without touching the saw. The carriage is 80 then in the position shown in Fig. 5. The turning of the valve 15 to move the port 23 in to registration with the passage 25 also moved the port 22 out of registration with the port 24 but moved the branch 29 85 of the exhaust passage 28, into registration therewith. A passage is now open for the exhaust steam from the left side of the cylinder 11 to pass through the ports 28 and 30 to the atmosphere. The continued movement of the axle 7 in the direction shown in Fig. 3 will carry the cam-ratchet 42 to the position shown in Fig. 4 in which the shoulder 47 has become disengaged from the shoulder 48 of the pawl 40 and the arm 36 90 has been moved over to its extreme left position, the valve 15 of each cylinder 11 now being set to a position in which it remains until the carriage 5 reverses again. The periphery of the disk 42 now acts as a cam 95 which holds the pawl 48 from engaging the notches 47. When the log carriage 5 reaches the end of its travel, as indicated by the arrow in Fig. 5, the carriage will reverse again and at this time, the shoulder 45 will become 100 engaged by one of the notches 44 of the cam-ratchet 41. The pawl frame 33 will again be shifted into the position shown in Fig. 2 and thus the valve 15 will be rotated back to the position shown in Fig. 7. Steam being 105 then admitted to the left side of the cylinder 11, will re-set the log carriage into position for another cut.

While I have illustrated and described the preferred construction and arrangement 110 of the device, obviously modifications and variations in the construction of the parts may be made without departing from the spirit of the invention or the scope of the claims.

I claim:—

1. The combination with a saw mill carriage, of a cylinder secured to the carriage, an axle passing through the cylinder and forming a support for the carriage, a piston 125

stationarily mounted on the axle and located within the cylinder, a valve mechanism associated with the cylinder, and means arranged on the carriage to operate the valve mechanism and admit steam into the cylinder at each side of the piston alternately and shift the carriage laterally on the axle.

2. The combination with a saw mill carriage, of a cylinder secured to the carriage, 10 an axle passing through the cylinder and forming a support for the carriage, a sleeve secured on the axle and passing through the cylinder, a piston head mounted on the sleeve and located within the cylinder, a steam 15 valve associated with the cylinder adapted to admit steam into the cylinder at either side of the piston, means located on the carriage adapted to operate the valve, and operating connections between the said operating 20 means and the valve.

3. The combination with a saw mill carriage, of a cylinder secured to the carriage at one end, an axle passing through the cylinder and forming a support for the carriage, a sleeve disposed on the axle and arranged to be held from endwise movement, 25 a piston head mounted on the sleeve and disposed within the cylinder, a valve chest associated with the cylinder and having a bore 30 and steam passages communicating with the bore and the cylinder at both sides of the piston, a valve located within the bore and having ports, a pawl frame located on the carriage and having connections with the 35 valve for moving the valve and admit steam into the cylinder at either side of the piston, and a cam-ratchet for operating the pawl frame upon reversal of the carriage.

4. The combination with a saw mill carriage, of a cylinder secured to the carriage 40 at one end, an axle passing through the cylinder and forming a support for the carriage, a piston head disposed within the cylinder and secured to the axle, a valve chest 45 associated with the cylinder the chest having a bore and passages communicating with the bore and with the cylinder at each side of the piston, a valve located in the bore the valve having ports and exhaust passages arranged in staggered relationship, a second 50 axle located on the carriage, a pawl frame supported on the carriage and having connections with the valve, and a cam-ratchet mounted on the second axle adapted to operate the pawl frame and shift the valve and bring one of the valve steam ports into registration with one of the steam passages 55 upon reversal of the carriage.

5. The combination with the track rails; 60 of a carriage arranged to move forwardly and backwardly thereover, an axle mounted at each end of the carriage, a centrally located axle mounted on the carriage, said axles having track wheels and forming supports for the carriage, a cylinder secured at

each end of the carriage, the end axles passing therethrough, a piston head secured on each of the axles, and arranged within its respective cylinder, a valve chest associated with each cylinder, a valve located in each 70 valve chest, notched disks mounted on the central axle, a pawl frame associated with the said disks, pawls arranged to engage the disks, connections arranged between the pawl frame and the aforesaid valves, said 75 disks and pawls being adapted to operate the valves and admit steam to the cylinders to shift the carriage laterally at the start of its forward and backward movements.

6. In a saw mill carriage; the combination with the central and end axles supporting the carriage, of steam cylinders secured at the ends of the carriage and through which the end axles pass, pistons fixedly mounted on the end axles and located within the cylinders, valve devices associated with the cylinders, a pair of cam-ratchets having shoulders arranged in opposite angular relationship, supporting bars at each side of the central axle, a pawl frame 90 mounted on the bars, pawls pivoted on the frame each engaging one of the cam-ratchets each of the pawls having a shoulder formed similarly to its coacting cam shoulder, means for holding the pawls in engagement with 95 the cam-ratchets, and connections between the pawl frame and valve devices.

7. In a saw mill carriage; the combination with the central axle, of rods disposed at each side of the axle and in parallelism therewith, a pair of disks mounted side by side on the axle the disks having notches cut in their peripheries the shoulders of the notches of the companion disks being disposed in opposite angular inclination, a 100 pawl frame supported by the rods, pawls fulcrumed on the frame each pawl engaging one of the disks, each pawl having a shoulder of corresponding angularity to the co-acting notch shoulder, one of the notch 105 shoulders of one of the disks being adapted to engage its co-acting pawl to pull the pawl frame over at the instant of reversal of rotation of the axle, and springs for holding the pawl in engagement with the disks.

8. In a saw mill carriage; the combination with the central axle, of rods disposed at each side of the axle, companion disks mounted side by side on the axle each of the disks having a plurality of notches in 110 their peripheries the shoulders of the notches of the companion disks being inclined in opposite directions, an arm mounted on each rod, a pawl fulcrumed on each of the arms, each pawl having a similarly 115 shaped shoulder which is adapted to engage one of the notches of its co-acting disk, a pawl bar joining the lower ends of the arms, a cylinder located at each end of the carriage, a valve device associated with each 120

125

cylinder, a connecting rod between the valve devices and the aforesaid pawl bar, one of the notches of one of the disks being adapted to engage its associated pawl to move the pawl bar and shift the valve devices.

9. In a saw mill carriage; the combination with the central axle, of rods disposed at each side of the axle, companion disks mounted side by side on the axle each of the disks having a plurality of notches in their peripheries the shoulders of the notches of the companion disks being inclined in opposite directions, an arm mounted on each rod, a pawl fulcrumed on each of the arms, each pawl having a similarly shaped shoulder which is adapted to engage one of the notches of its co-acting disk, a pawl bar

joining the lower ends of the arms, a cylinder located at each end of the carriage, a valve device associated with each cylinder, 20 a connecting rod between the valve devices and the aforesaid pawl bar, one of the notches of one of the disks being adapted to engage its associated pawl to move the pawl bar and shift the valve devices, the said 25 disk being arranged to act as a cam to throw the pawl into disengagement upon continued movement of the disk in the same direction.

EDWARD AMOS HARRIS.
